UNITED STATES PATENT OFFICE.

DANIEL SHAW WAUGH, OF CHICAGO, ILLINOIS.

AUTOMATIC VALVED HAMMER.

SPECIFICATION forming part of Letters Patent No. 701,235, dated May 27, 1902.

Application filed November 30, 1900. Serial No. 38,201. (No model.)

To all whom it may concern:

Be it known that I, DANIEL SHAW WAUGH, a citizen of the United States, residing at Chicago, in the county of Cook and State of Illinois, have invented a new and useful Automatic Valved Hammer, of which the following is a specification.

This invention relates to a novel automatic hammer comprehending a shell or casing, a reciprocatory hammer therein, and automatically-operated valve mechanism regulating the supply of a fluid motive agent—such as compressed air, gas, or the like—to the opposite ends of the casing or shell to effect the reciprocation of the hammer.

The object of the invention is to produce a long-stroke valved hammer having a piston or hammer proper of light weight and capable of attaining great velocity on its downstroke with comparatively little vibration of the device as a whole. These ends are attained by the construction to be hereinafter described, embodying a comparatively long shell fitted at one end with a tool-holder, a small comparatively light hammer disposed within the shell, means whereby the effective pressure of the motive agent is exerted upon a reduced area of the piston during the initial portion of its downstroke, which area is increased during the downward movement of the hammer, means for relieving the compression opposed to the piston during the final portion of its return movement, a novel arrangement of valve mechanism facilitating the automatic control of the motive fluid, and a novel form and arrangement of the initial valve and its trigger to enable the operator to regulate with great nicety the amount of fluid admitted to the device, and consequently the force exerted by the hammer upon the tool.

The invention further consists in certain features of construction and arrangement to be more fully described, illustrated in the accompanying drawings, and defined in the claims.

In said drawings, Figure 1 is a longitudinal section through the device complete, certain of the parts—as, for instance, the handle and tool-holder—being shown in elevation and the hammer being located at the lower or outer limit of its effective stroke. Fig. 2 is a view similar to Fig. 1, showing the hammer at or

adjacent to the opposite end of its movement and the several valves shifted to their opposite positions. Fig. 3 is a sectional elevation of the upper end of the instrument, illustrating the arrangement of one of the fluid passages or ports.

Referring to the numerals employed to designate like parts throughout the several views, 1 indicates the shell or casing, which is preferably of cylindrical form and has its upper end closed by the head 2 and fitted in its opposite end with a tapering steel bushing 3, surrounding the shank 4 of the tool-holder 5, designed for the reception of a suitable tool, which is to be operated by successive blows from a piston or hammer 6, disposed to reciprocate within the shell. The head 2 is provided with a cushioning-plug 7, extending into the upper end of the shell 1 for reception within the compression-chamber 8 of the hammer 6 for a purpose to be described. This head may be secured to the shell in a variety of ways; but I prefer to effect its attachment by means of a surrounding and surmounting cap 9, carrying the handle 10 and having an externally-threaded flange 11, engaged by a split ring or collar 12, internally threaded for engagement with the flange 11 of the cap and designed to be drawn up by means of a bolt 13. At its lower edge the collar 12 is formed with an internal annular flange 14, taking under an external flange 15 at the upper end of the casing in order to preclude the possibility of the accidental displacement of the cap and head from the shell. At a point above the upper end of the shell 1 the head 2 is provided with a transversely-disposed valve chest or cylinder 16, communicating with the interior of the shell at opposite ends thereof through principal ports 17 and 18. The port 17 passes longitudinally through the cushioning-plug 7 and opens into the shell at the lower end of said plug, while the other principal port 18 is disposed longitudinally within the wall of the shell and communicates with the interior of the latter at its extreme lower end, said port by reason of its lateral position with respect to the axis of the shell or casing being provided at its upper end with a lateral extension 19, formed in the head 2 and communicating with the interior of the valve chest or cylinder directly below

the axis thereof, but at a point removed from the port 17, as clearly shown in Figs. 1 and 3. The cap 9 is provided above the head with a supply-chamber 20 and around said head, 5 adjacent to its upper edge, with an exhaust-chamber 21, the latter discharging through an exhaust-port 22, piercing the wall of the cap. The supply-chamber 20 communicates with the interior of the valve-chest 16, at the 10 center of the latter, through a supply-port 23 and is also in communication with what may be termed an "initial" supply-port 24, formed in the cap and having its disaligned end portions bisected by an intermediate 15 valve-chamber 25, within which is disposed the initial valve 26, arranged to seat upon a tapering valve-seat 27 and provided with an extended stem 28. The extremity of the valve- 20 stem 28 extends beyond the face of the cap into effective proximity to the short end of a valve lever or trigger 29, pivoted between a pair of ears 30 upon the cap and provided with a handle or finger piece 31, disposed adjacent to the lower end of the shank 32 of 25 the handle 10 in order that the workman, holding the device by the handle 10, may insert the forefinger of the hand thus employed in the ring 31 for the purpose of controlling with great nicety the admission of motive 30 fluid by the manipulation of the valve. At opposite sides of the port 23 the wall of the valve-chest 16 is pierced by exhaust-ports 21^a and 21^b, which are extended through the head to communicate with the exhaust-chamber 21, 35 discharging, as already stated, through the exhaust-port 22.

We have now seen that the interior of the valve-chest 16 is in communication with the opposite ends of the shell or casing and also 40 with fluid supply and exhaust chambers, the former of which is designed to receive motive fluid from a supply-pipe 33, screwed into the outer end of the port 24. It will therefore appear that some means must be provided for establishing communication between the opposite ends of the casing and the supply and exhaust chambers alternately. 45 The means which I prefer to employ for this purpose is embodied in a piston-valve 34, provided with terminal valve-heads 21^c and 21^d, controlling the exhaust-ports 21^a and 21^b, and an intermediate valve-head 23^a, controlling the port 23. The intermediate or central valve-head 23^a of the piston-valve is of 50 somewhat greater diameter than the terminal heads and is received within a central enlargement 35 of the valve-chest, the ends of this enlargement being disposed at or about the axes of the principal ports, so that as the piston-valve is shifted to one end or the other of the valve-chest these principal ports will be 55 in communication either with the supply-port 23 or with one of the exhaust-ports. Thus if the piston-valve is in the position shown in Fig. 1 and the initial valve 26 is opened 60 the motive fluid will be admitted to the supply-chamber 20 and thence through the port

23 to the interior of the valve-chest. The fluid—as, for instance, compressed air—will thus escape to the interior of the shell at its 70 upper end through the principal port 17 and will force the hammer to a position at the lower or outer end of the casing, as shown in Fig. 1. It will now appear that if the motive fluid thus admitted to the interior of the 75 casing above the hammer is exhausted and live fluid is admitted to the interior of the casing below the hammer the latter will ascend to its initial position. In order to do this, however, the piston-valve 34 must be 80 shifted to the position indicated in Fig. 2 of the drawings, first, to permit the fluid above the hammer to exhaust through the port 21^b and, second, to establish communication between the principal port 18 and the supply- 85 port 23. Consequently some means for effecting the automatic shifting of the valve must be provided. In the present device this means for shifting the valve comprehends a pair of auxiliary ports 36 and 37, extending longitudinally within the wall of the casing and extended farther to communicate with the interior of the valve-chest at the opposite ends thereof, so that as air or other expansible fluid is admitted to the chest 90 through one or the other of the auxiliary ports the piston-valve will be shifted to one or the other of its two positions. The port 36 opens into the shell immediately above the hammer in the lower or outer position of the 95 latter, as shown in Fig. 1, and the port 37 communicates with the interior of the shell just below the hammer when the latter is at the opposite end of its stroke, as shown in Fig. 2. Thus it will appear that as the hammer descends under the impulse of the fluid agent admitted through the port 17 it will 100 finally uncover the auxiliary port 26 to permit the escape of the motive fluid through said port 36 to shift the valve to the position indicated in Fig. 2 of the drawings, thereby establishing communication between the port 17 and the exhaust-port 21^b and also placing the port 18 in communication with the supply to admit the motive agent below the hammer for the purpose of effecting its return. 105 It is evident, however, that the hammer in descending would first uncover the port 37, and therefore provision must be made for closing said port automatically and for maintaining 110 such closure until the hammer has reached the limit of its downward movement, and by a parity of reasoning it is equally evident that the port 36 must be closed during the upward movement of the hammer and until 115 the latter has reached the upper limit of its movement. I therefore dispose within the head 2 a pair of spring-pressed auxiliary valves 36^a and 37^a, preferably of cylindrical form, as shown, and disposed within valve-chambers 36^b and 37^b, the former of which is 120 in communication with the extension 19 of the port 18 and the latter in similar communication with the port 17. The effect of this 125 130 135

arrangement will be to cause either of these auxiliary valves to be closed against the resistance of its spring whenever the principal port with which the valve is associated is being utilized for the admission of the motive fluid or agent to the interior of the shell. This will be readily apparent when we consider the arrangement of the parts as shown in Fig. 1. In this figure the motive agent is being admitted to the interior of the shell through the principal port 17, and as the auxiliary-valve chamber 37^b is in communication with this principal port sufficient pressure will be exerted upon the auxiliary valve 37^a to move it to a position across the auxiliary port 37, as shown. Thus the uncovering of the port 37 as the hammer descends will not effect the exhaust of the motive fluid from above the hammer. As soon, however, as the hammer descends sufficiently to uncover the auxiliary port 36 the motive fluid will exhaust through said port, because the valve 36^a is open, and will pass to the interior of the valve-chest to shift the valve 34 to the position shown in Fig. 2. This shifting of the piston-valve will direct the motive fluid into the principal port 18, thus forcing the auxiliary valve 36^a to close the auxiliary port 36 and will at the same time permit the motive fluid above the hammer to exhaust through the port 21^b, thus removing the pressure from behind the auxiliary pressure-valve 37^a and permitting said valve to open, as shown in Fig. 2. The motive fluid admitted below the hammer through the upper port 18 will now urge the hammer upwardly; but as the port 36 is closed the uncovering thereof by the ascending of the hammer will have no effect, and the piston or controlling valve will not be again shifted until the hammer has uncovered the port 37, at which time the operation just described will be reversed, and the hammer will again descend.

It will now be clear that the piston or hammer will be driven toward the tool by the application of fluid-pressure to a comparatively reduced area of the hammer, this initially-effective area being merely that of the bottom of the cavity or chamber 8. This reduction of the effective pressure area is due to the fact that the cushioning-plug 7 extends into the hammer cavity or chamber 8, and the motive fluid is admitted to the interior of the cavity through the port 17, thus preventing the exertion of the fluid-pressure upon the annular upper end of the hammer disposed within the space defined between the cushioning-plug and the wall of the shell. This desirable reduction of the effective area of the hammer during the initial portion of its downward or effective stroke is accompanied by a correspondingly disadvantageous compression opposed to the return movement of the hammer as it nears the end of its return stroke, this by reason of the fact that as the hammer moves into engagement with the cushioning-plug the annular space defined

around the plug and above the hammer is cut off from communication with the exhaust, and as a consequence the occluded air will be compressed by the continued upward movement of the hammer and by its compression will exert such resistance to said hammer as will produce more or less vibration the elimination of which is one of the primary objects of the invention. In order to relieve this compression or fluid resistance to the return of the piston, I form the shell with what may be termed a "relief" or by-pass port 38, disposed longitudinally in the wall of the shell and opening therein immediately below the head 2 and also at such distance below the head as will cause the hammer to uncover the lower end of this port as said hammer moves into engagement with the cushioning-plug. Thus the air which would otherwise be compressed above the hammer escapes through the port 38 to the interior of the shell below the hammer and is exhausted therefrom in the manner described.

For the purpose of preventing the tool-holder 5 from dropping out of the shell when it is not in use I form a pair of annular flanges 5^a and 5^b upon the holder 5 and dispose between them the beak of a spring-pressed pivoted latch 39, carried at the lower end of the shell, as shown.

Before concluding the description of the device it may be well to state that the enlargement or central head 23^a of the valve 34 is calculated to steady the movement of the valve as it is shifted from one position to the other. When this valve is at either end of its stroke, one side face of the central enlargement 23^a is subjected to pressure while the space at the opposite side thereof is in communication with one of the exhaust-ports. This pressure upon the central enlargement is overcome by the pressure of air at one end of the valve by reason of the provision of the ports 36 and 37, and if it were not for the enlargement 23^a the leak of air around the valve ends would cause it to flutter, thereby interfering with the operation of the hammer.

From the foregoing it will appear that I have produced a simple and ingenious long-stroke valved hammer of the automatic type embodying a construction well adapted for the reduction of the vibration of the instrument and for the attainment of a high velocity and the exertion of great striking force by a hammer of comparatively small size and light weight compared with the length of the stroke; but while the construction and arrangement of parts described and illustrated are thought at this time to be preferable I desire to be distinctly understood as reserving the right to effect such variations or modifications of the described structure as may be properly comprehended within the scope of the appended claims.

What I claim is—

1. In a fluid-operated hammer, the combination with a casing, a hammer movable there-

- in, means for effecting the supply and exhaust of a motive fluid to and from the casing, and means for reducing the area of the surface of said hammer exposed to the motive fluid at one limit of movement of the hammer, of means formed in the casing for relieving the compression opposed to the hammer during the final portion of its return movement said means being supplemental to the normal exhaust.
2. In a fluid-operated hammer, the combination with a casing provided with a cushioning-plug extended therein, of a chambered hammer disposed to move within the casing and to receive the cushioning-plug, means for effecting the supply and exhaust of the motive fluid to and from the casing to operate the hammer, and means separate from the normal exhaust for relieving the compression opposed to the return of the hammer.
3. In a fluid-operated hammer, the combination with a casing provided with an inwardly-projecting cushioning-plug, of a chambered hammer mounted for reciprocation within the casing and designed to receive the plug, means for effecting the supply and exhaust of the motive fluid to and from the casing to operate the hammer, and a relief-port piercing the casing at a point above the inner end of the cushioning-plug and also opening into the casing at a point below or beyond the hammer when the latter is engaged with the plug.
4. In a fluid-operated hammer, the combination with a casing provided with principal ports opening into the opposite ends of the casing, a controlling-valve controlling the supply and exhaust through said principal ports, auxiliary ports opening into the casing and disposed to admit fluid to the controlling-valve, and means controlling the passage of fluid through said auxiliary ports, said means being controlled by the fluid-pressures within the principal ports.
5. A fluid-operated hammer comprising a casing, a valve-chest, a pair of principal ports leading from the valve-chest to the interior of the casing, auxiliary ports leading from the casing to the opposite ends of the valve-chest, a controlling-valve within the valve-chest, automatically-operated auxiliary valves controlling the auxiliary ports, and a hammer mounted for reciprocation within the casing.
6. A fluid-operated hammer comprising a casing, a valve-chest, a pair of principal ports, and a pair of auxiliary ports, all of said ports opening into the casing and valve-chest respectively, a controlling-valve within the valve-chest, auxiliary valves controlling the auxiliary ports, means for supplying pres-

sure from the principal ports to operate the auxiliary valves, and a hammer mounted for reciprocation within the casing.

7. In a fluid-operated hammer, the combination with a casing provided with a valve-chest and valve, a pair of principal ports communicating with the opposite ends of the casing and with a pair of auxiliary ports also communicating with the interior of the casing, all of said ports being in communication with the valve-chest, a piston-valve within the valve-chest controlling the supply and exhaust of the motive fluid to and from the ports, auxiliary-valve chambers intersecting the auxiliary ports and in communication with the principal ports, spring-pressed valves within said valve-chambers, a hammer mounted for reciprocation within the casing, and means for supplying and exhausting the motive fluid to and from the valve-chest.

8. In a fluid-operated hammer, the combination with a casing, a valve-chest disposed at one end thereof, supply and exhaust chambers disposed upon the exterior of the valve-chest and communicating therewith, principal and auxiliary ports communicating with the interior of the casing and with the valve-chest, automatically-operated valves controlling the several ports, a hammer mounted for reciprocation within the casing, a supply-port communicating with the supply-chamber, said port being intersected by an initial valve-chamber having a tapering valve-seat, an initial valve opposed to said seat, a trigger disposed beyond the casing and in operative relation with the initial valve, and a handle connected to the casing and disposed in convenient relation to the trigger.

9. In a fluid-operated hammer, the combination with a casing, a valve-chest disposed at one end thereof, a valve within the valve-chest, and a hammer within the casing, of a head closing the valve-chest and provided with a supply-port intersected by a valve-chamber having a tapered seat, a valve opposed to the seat and provided with an extended stem, a pivoted trigger mounted upon the head and provided with an operating end disposed at one side of said head, and a handle extended from the head at the side adjacent to the operating end of the trigger and extended over the trigger to protect the same.

In testimony that I claim the foregoing as my own I have hereto affixed my signature in the presence of two witnesses.

DANIEL SHAW WAUGH.
